[57] **CLAIM**

The ornamental design for a decorative connector between an earring and a hair appliance, as shown and described.

DESCRIPTION

FIG. 1 is a perspective view of the decorative connector between an earring and a hair appliance showing my new design; and,

FIG. 2 is a front perspective view, the rear view being a mirror image thereof, shown on an enlarged scale.

The broken line showing of a human head in FIG. 1 and an ear and earring in FIG. 2 are for illustrative purposes only and forms no part of the claimed design.
